BUFFING WHEEL OF WOVEN FABRIC WITH WARP YARNS ARRANGED RADIALLY, AND METHOD OF MAKING SAME

William J. Miller, Conover, N.C., assignor to Jackson
Buff Corporation, a corporation of North Carolina
Filed Jan. 10, 1962, Ser. No. 165,378
3 Claims. (Cl. 51—193)

The present invention relates to an improved buffing wheel and the method of making same, and more particularly to a buffing wheel made of woven fabric with the fabric arranged so that the warp yarns extend radially with respect to the buff to position the ends of the warp yarn against the article being buffed and thereby provide improved buffing action.

At the present time woven buffing material is conventionally cut along a bias and the material formed into a buffing wheel with the bias cut edge at the periphery of the buffing wheel, thereby presenting both the warp and filling yarns at 45° angles to the periphery and to the work piece. Heretofore this bias arrangement has been considered as providing the most desirable buffing action.

However, we have discovered that a significant improvement in buffing action is obtained by arranging the woven buffing fabric with the warp yarns extending radially, which presents the ends of the warp yarns perpendicular to the periphery of the buffing wheel. This arrangement of the warp yarn, which is generally stronger and more durable than filling yarn, provides increased strength, durability and buffing action. In addition, this arrangement positions the filling yarn annularly so that only the outer filling yarns will be acting against the work piece while the inner filling yarns will remain woven with the warp yarns to hold the warp yarns in place. This is an advantage over bias cut buffing material wherein the filling yarns, as well as the warp yarns, are arranged with their ends exposed to the work, with the result that the filling yarns are pulled from their woven positions by the buffing action, causing the weave to open and the buff to break down.

The present invention is applicable to all types of buffs made with woven fabric. In the preferred embodiment the present invention is incorporated in a buffing wheel having a plurality of woven fabric layers with the edges of the layers at the periphery of the buffing wheel, and with the fabric arranged so that the warp yarns are extending radially with respect to the wheel and the filling yarns are extending annularly.

This buffing wheel is formed from woven buffing material, cut fillingwise into strips and with the strips secured together endwise to form a continuous strip having filling yarns extending longitudinally and warp yarns extending transversely. This continuous strip is then wound upon itself to form a multi-layer tube with the warp yarns extending longitudinally of the tube. The middle of the tube is then drawn in and the edges of the tube folded outwardly to present the edges of the layers in a circular periphery with the warp yarns extending radially and the filling yarns extending annularly. These layers are then secured in a base for use in a buffing operation.

The features and advantages of the present invention will be apparent from the following description and accompanying drawings in which:

FIG. 1 is a side elevational view of a buffing wheel incorporating the preferred embodiment of the present invention and showing a portion of the buffing wheel against a work piece;

FIG. 2 is an enlarged view of a portion of the periphery of the buffing wheel of FIG. 1;

FIG. 3 is a view similar to FIG. 2 showing the buffing wheel against a work piece;

2

FIG. 4 is a plan view, partially broken away, of a sheet of woven buffing fabric and indicating the lines along which it is to be cut to form strips for use in the formation of the buffing wheel of the present invention;

5 FIG. 5 is a top plan view, partially broken away, of a continuous strip of buffing fabric formed from strips cut from the fabric of FIG. 4, with their ends secured together; and

FIG. 6 is a perspective view of a cylindrical form with a continuous strip partially wound thereon preparatory to forming of the strip into the buffing wheel of the present invention.

For purposes of illustration the present invention is shown incorporated in a buffing wheel 10 of the type shown in FIG. 1. This buffing wheel 10 comprises an outer buffing portion 12 formed of a plurality of layers of woven buffing material. The outer buffing portion 12 is mounted in an inner supporting base or lacing 14 which holds the layers of the buffing portion 12 together to form a unitary buff. If desired, the lacing 14 may be secured in a hub (not shown) with the hub being mounted on a shaft and the shaft being driven to cause rotation of the buffing wheel 10 and provide a buffing action when the periphery of the buffing wheel 10 is directed against a work piece, such as that illustrated in 16 in FIG. 1.

As seen in FIGS. 2 and 3 the woven buffing material of the outer buffing portion 12 is arranged with warp yarns 18 extending radially with respect to the buffing wheel 10 and filling yarns 20 extending annularly with respect to the buffing wheel. Thus the ends 22 of the warp yarns 18 are presented perpendicular to the periphery of the buffing wheel 10 and will be directed against the work piece 16 when the buffing wheel 10 is rotated thereagainst.

35 Also as seen in FIGS. 2 and 3 the filling yarns 20 extend annularly with respect to the buffing wheel 10 and only the outer filling yarns will be in a contact with the work piece 16.

The buffing wheel of the preferred embodiment of the present invention is formed from a sheet 24 (FIG. 4) of woven buffing material. This sheet 24 is cut along spaced lines 24 extending parallel to the filling of the woven sheet 24 to form strips 28 having warp yarns extending transversely and filling yarns extending longitudinally. These strips 28 are secured together to form a continuous strip 30 by securing the ends 32 of the strips 28 together, as by stitches 34.

50 The continuous strip 30 is then formed into the outer buffing portion 12 of the buffing wheel 10 on a cylindrical form 36. The continuous strip 30 is wound flat on the surface of the cylindrical form 36 a number of times to provide the desired number of layers in the outer buffing portion 12. The cylindrical form 36 is formed with a slot 38 in its periphery at the middle of the wound strip 30 so that the strip 30 can be drawn into the slot 38 by a drawstring or other conventional forming mechanism, thereby folding the strip 30 upon itself to position the layers in a radial plane with their edges 40 forming a circular outer periphery. When the strip 30 is wound on the form 36 the warp yarns extend longitudinally of the form and as a result when the strip is drawn in on the form the warp yarns will be arranged to extend radially.

55 The form 36 may be made in separable halves so that the form can be removed from the drawn in strip 30. The lacing 14 is then secured to the inner edge of the layers 12 and the layers are secured together by stitching 42 adjacent the lacing 14.

60 In one example of the present invention the buffing wheel is formed from a sheet of conventional 250 weight woven buffing fabric having a thread count of 86 x 93. The sheet is 40 inches wide and is cut along the filling

at 10 inch intervals to form strips 40 inches long and 10 inches wide. These strips are sewn together at their ends to form a continuous strip which is formed into a buff using a conventional forming drum.

The present invention has been described above for purposes of illustration only, and is not intended to be limited by this description or otherwise except as defined in the appended claims.

I claim:

1. A buffing wheel having a central base portion and an outer buffing portion supported on said base portion, said buffing portion comprising a continuous strip of non-spiral woven buffing fabric formed of a plurality of strips secured together endwise with their warp yarns extending transversely to the length of the strip, said continuous strip folded lengthwise with the fold abutting the base portion and the fabric on either side of the fold arranged edgewise with respect to the base portion and extending a plurality of times around said base portion to provide a plurality of layers, said fabric having warp 20 yarns extending radially and filling yarns extending annularly.

2. A method of forming a buffing wheel comprising cutting woven buffing fabric fillingwise into strips, securing said strips together endwise to form a continu- 25

ous strip, winding said strip to form a multi-layer tube, drawing in the middle of the tube between its ends to fold the layers of the tube to extend perpendicular to the axis thereof with the warp yarns extending radially and the filling yarns extending annularly, and securing the inner edge of said wound strip in a supporting base.

3. A method of forming a buffering wheel comprising cutting woven buffering fabric fillingwise into strips, securing said strips together endwise to form a continuous strip, winding said strip a plurality of times around a cylindrical form to provide a plurality of layers of fabric on the form with warp yarns extending parallel to the axis of the cylindrical form, drawing said wound strip into an annular slot in the form to fold said plurality of layers into a radial plane and position said warp yarns radially and the filling yarns annularly, and securing the inner edge of the folded layers in a supporting base.
